By his Attorneys,

John Hankin,

W. S. Duval.

Cadmon & Co.

UNITED STATES PATENT OFFICE.

JOHN HANKIN, OF RUTHERFORD, NEW JERSEY.

CAR-VENTILATOR.

SPECIFICATION forming part of Letters Patent No. 503,047, dated August 8, 1893.

Application filed March 23, 1893. Serial No. 467,317. (No model.)

To all whom it may concern:

Be it known that I, JOHN HANKIN, a citizen of the United States, residing at Rutherford, in the county of Bergen and State of New Jersey, have invented a new and useful Ventilator for Cars, of which the following is a specification.

My invention relates to improvements in ventilators for railway cars; the objects in view being to provide a cheap and simple device adapted to be mounted conveniently upon the roofs of cars and so constructed as to prevent the admission of rain, snow, sleet, &c., or any cold drafts, and yet at the same time be adapted to provide an exhaust for the interior of the car regardless of the direction of travel of the car, whereby all foul air will be withdrawn from the car and pure air admitted.

With these general objects in view the invention consists in certain features of construction hereinafter specified and particularly pointed out in the claims.

Referring to the drawings:—Figure 1 is a perspective view of a ventilator constructed in accordance with my invention. Fig. 2 is a vertical longitudinal sectional view of the same. Fig. 3 is a vertical transverse sectional view thereof.

Like numerals of reference indicate like parts in all the figures of the drawings.

In carrying out my invention I employ a sheet-metal casing 1, the same being of inverted triangular shape and at its three angles provided with openings. The upper openings 1 and 2' are longitudinally opposite each other, while the lower opening 3 communicates with the interior of the car and is surrounded by a securing flange extending at a right angle to the casing and adapted to be secured to the roof of the car. Upon the inside of the casing above the opening 4 the same is provided with an internal surrounding gutter or trough 5 which communicates with the exterior through a series of minute perforations 6 provided in the casing at the base of the gutter or trough. This gutter is intended to receive any moisture that may find its way into the casing and conduct the same to the outside. The upper side of the casing is provided with an elliptical opening

7, and surmounting the same and spaced therefrom is a convexed cap 8, brackets being employed at intervals for supporting the cap above the casing so that a space is produced 55 entirely around the cap, and between it and the casing. At opposite ends of the cap stops 9 are located upon the inner side of the casing, and at diagonally opposite points similar stops 10 are located near the bottom of the 60 casing. At a point between the diagonal stops a transverse shaft 11 is located, and upon this shaft is loosely mounted a rocking-damper 12, the major portion of whose area is above the shaft, whereby it is adapted to be thrown to 65 either side of the opening 7 in the upper side of the casing by the pressure of air thereagainst and hence establish communication between the interior of the car and either one of the two end openings 2 and 2', and cut off 70 communication with the remaining opening. At the lower end of the ventilator-casing a register 16 is located by which the draft of air may be regulated. In transverse supports or bars 13, which cross the openings 2 and 2', is 75 supported a longitudinal shaft 14, which passes through the damper and provides bearings in each of the openings 2 and 2' for a pair of rotatable fan-wheels 15. This completes the construction, whose operation may be 80 briefly stated as follows: For example, we will presume that the car is moving in the direction of the large arrow X, when it will be seen that the fan-wheel 15 in the opening 1 will be revolved, the air passing in the direction of 85 the small arrows, through the same, and out under the cap of the casing, while the fan 15 of the opening 2' will serve as an exhaust fan, and thus exhaust the foul air in the coach below making room for pure fresh air. The 90 damper is automatically thrown at its top in the direction opposite the direction of movement of the car. In this manner a most effective ventilation is constantly carried on and the coach maintained pure and healthy. If 95 the car should be running in the opposite direction the damper is automatically reversed, that is swung to the position shown in dotted lines, so that the opening 2' is cut off from communication with the car and the opening 100 2 placed in communication therewith, and the air exhausts from the car in the same man-

ner regardless of the direction of travel of the car or coach. It will be seen that any moisture that may gain access to the casing will be caught by the sides of the casing or the damper, 5 and the latter being above the gutter or trough will shed the same into the gutter or trough whereby it will be collected and carried off through the perforations 6 onto the roof of the car.

10 Having described my invention, what I claim is—

1. The combination with the substantially triangular casing having openings at its three angles and upon its upper side, of a longitudinal shaft loosely journaled in the two longitudinally opposite openings, the two wheels carried by the shaft a cap arranged over the upper opening, and a damper pivoted in the casing between the longitudinally opposite 20 openings and extending diagonally across said casing, whereby either of said longitudinally opposite openings may be thrown into communication with the lower opening, substantially as specified.

25 2. The combination with the triangular casing 1 having the longitudinally opposite openings 2, 2' the lower inlet opening 3 and the upper exit-opening 7, of the cap 8 arranged over the opening 7 and out of contact with

30 the casing, the shaft 11 passing through the casing, the damper 12 loosely mounted below its center on the shaft, the diagonally oppo-

site pairs of stops 9 and 10, the former arranged at opposite sides of the opening 7, the gutter or trough arranged around the interior 35 of the casing below the damper and opposite perforations formed in the casing, the cross-bars 13 in the openings 2 and 2', the shaft connecting the cross-bars and passing through the damper, the exhaust-fan-wheels mounted 40 on and adapted to revolve with the shaft in the openings 2 and 2', and the register at the lower end of said casing, substantially as specified.

3. In a car ventilator, the casing having 45 openings at opposite ends and at the bottom, the bottom opening communicating with the interior of the car, and the end openings serving in one case as an inlet and in the other as an outlet, in combination with the fans or 50 wheels located in the end openings, and the automatically controlled damper pivoted intermediately between the end openings so as to shut off communication between the same and at the same time establish communication 55 between the bottom opening and one of the end openings, substantially as specified.

In testimony that I claim the foregoing as my own I have hereto affixed my signature in the presence of two witnesses.

JOHN HANKIN.
